Primary Examiner — Dana K Weiland*Assistant Examiner* — Jonathan E Fiencke(74) *Attorney, Agent, or Firm* — MYERS WOLIN, LLC(57) **CLAIM**

The ornamental design for a HUMIDIFIER as shown and described.

DESCRIPTION

FIG. 1 is a top front right perspective view of a HUMIDIFIER showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a top front right perspective view of a second embodiment of a HUMIDIFIER showing our new design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top view thereof; and

FIG. 14 is a bottom view thereof.

The evenly spaced broken lines and unshaded areas within depict portions of the HUMIDIFIER that form no part of the claimed design.
